FRIEDRICH PROCHASKA, OF CHARLOTTENBURG, GERMANY, ASSIGNOR TO SIEMENS & HALSKE A. G., OF BERLIN, GERMANY, A CORPORATION OF GERMANY.

RAIL-CIRCUIT-CLOSING CONTACT.

1,072,030.

Specification of Letters Patent.

Patented Sept. 2, 1913.

Application filed June 17, 1909. Serial No. 502,787.

To all whom it may concern:

Be it known that I, FRIEDRICH PROCHASKA, a subject of the Emperor of Austria-Hungary, and residing at Charlottenburg, 5 near Berlin, Germany, have invented certain new and useful Improvements in Rail-Circuit-Closing Contacts, of which the following is a specification.

My invention relates to rail circuit-closing contacts of the well-known mercury type, in which the downward deflection of the rail by the weight of the passing train is utilized for producing an electric contact by pressing mercury from a pressure vessel 15 into an adjoining contact vessel in which an electric contact takes place.

In the art the arrangement is generally such that the pressure vessel is closed at the top by a steel diaphragm, upon which the 20 pressure, exerted by the downward deflection of the rail, is transmitted. This arrangement has the disadvantage that owing to the reaction produced by the inertia of the mercury, the diaphragm suffers what 25 might be termed hereinafter a counter deflection which tends to distort the diaphragm oppositely to the direction in which the rail tends to distort or deflect it, and owing to this counter deflection a considerable 30 amount of the motion produced by the deflection of the rail and intended to be transmitted to the mercury is neutralized and thus unavailable, and as a result too little mercury is pressed into the contact 35 vessel.

In order to render the reaction of the mercury ineffective the pressure vessel, according to the present invention, is not covered with a diaphragm but with a strong 40 heavy metal plate, the thickness of which is chosen so that the plate will bend only under the weight of the load which the car wheel carries and that the reacting pressure caused by the inertia of the mercury is unable to 45 produce an undesirable counter deflection of the plate.

In order to clearly explain my invention I have illustrated same in the accompanying drawings in several modifications.

50 In these drawings: Figure 1 shows a form of my improved rail contact in transverse sectional elevation. Fig. 2 is a side elevation thereof. Fig. 3 is a side elevation of a rail portion with the rail contact interposed

directly between the rail and the sleeper. 55 Fig. 4 is a transverse sectional elevation of a modification of the form shown in Fig. 1, in which the girder which supports the rail contact forms a part of the pressure chamber. Fig. 5 is a transverse sectional elevation of another modification in which intermediate members are placed between the rail and the contact device to transmit the pressure from the rail to the latter, and Figs. 6 and 7 are diagrams showing a difference in 60 effect on the elastic line of a plate when a comparatively large intermediate member exerts a pressure upon the walls of a chamber and when a comparatively small intermediate member bears centrally against the 65 walls of a pressure chamber.

Referring to Figs. 1 and 2, the contact device consists of two thick iron or steel plates 5 and 7 recessed at the surfaces facing each other so that a chamber 8 is formed between 75 these plates when they are placed on top of each other. These plates are placed between the underside of the rail 1 and girder 2 which latter is held tight to the rail by means of clamps 3 which can be tightened 80 by means of screws 4. The upper plate 5 has laterally of the rail near its rim a thickened portion 9 which is provided with a short duct 10 terminating with its lower end in chamber 8 and with its upper end in 85 the contact vessel 11. Chamber 8 is completely filled with mercury and the duct to a suitable height as shown. The train in passing over rail 1 depresses this rail so that plates 5 and 7 are deflected toward each 90 other which diminishes the volume of chamber 8 so that the mercury in duct 10 rises and contact is made in contact vessel 11 with contact pin 12, by having the mercury squirted against this pin. The mercury thus 95 ejected from the duct 10 returns to chamber 8 by way of compartment 13. Contact devices of this character are known in the art and the above construction is only shown as an example and may be substituted by any 100 known similar device. The two plates 5 and 7 may be fastened together at their rims in any suitable manner as for instance by welding or bolting (not shown here). Moreover any suitably shaped iron bar or rail 105 may be used for supporting the two plates which contain the pressure chamber 8 but I prefer a rail having a profile similar to that

of a railroad rail, such as is shown at 2 in Fig. 1. The arrangement of the device is clearly shown in side view in Fig. 2.

Inasmuch as a pressure vessel constructed in the manner just described is capable of sustaining a great pressure the supporting girder 2 may be omitted and a pressure vessel 5, 7 of the kind shown in Figs. 1 and 2 may be placed directly between the railway rail and the sleeper 6 as shown in Fig. 3. The top surface of supporting girder 2 may be utilized as a wall for the pressure chamber 8 on which then plate 5 rests as a top plate with otherwise a similar construction as that shown in Fig. 1. This modification is represented in Fig. 4.

The amount of mercury expelled from chamber 8 by the pressure of a passing train may be considerably increased by interposing between the rail and the upper plate 5 of the pressure vessel an intermediate member which I shall call hereinafter the presser, and the pressure vessel may be supported at its under side again by a rail 2, which, however, is shaped at its upper side where it contacts with the pressure vessel similarly to presser 17. This modification is illustrated in Fig. 5 where the presser is shown at 17 and the supporting rail at 2^a. It will be noted from this figure that presser 17 and rail 2 are provided with rims *a* with which alone they bear against their respective plates 5 and 7 so that they do not abut against the centers of the pressure plates 5 and 7. Moreover the presser 17 preferably does not abut against the rail 1 with a large surface but a hemispherical equalizing member 18 is interposed between the foot of the rail and the presser 17 so that in case the device should not be properly aligned the pressure of the rail is not exerted one sidedly against the presser 17. If this were the case the heavy pressure exerted by the train might be transmitted from the rail 1 to presser 17 at one side only and at a few points at that, which might cause the rail flange or the presser to yield or become indented under the extremely high specific pressure which in turn would lessen the pressure transmitted to the mercury in chamber 8. With the hemispherical member 18 interposed the pressure will always be symmetrically distributed over presser 17 and in turn be symmetrically transmitted to plate 5. This arrangement works to a particular advantage.

The reason why with a presser, a larger amount of mercury may be expelled from chamber 8 may be clearly seen from the diagrams shown in Figs. 6 and 7. In Fig. 6 the dotted lines which represent the exaggerated deflection of plates 5 and 7 are produced when a construction is employed such as shown in Fig. 5 in which the rail pressure is transmitted through a presser

17 whereas the elastic lines of plates 5 and 7, shown in Fig. 7, are produced when the pressure of the rail is imparted directly from the rail centrally to the pressure plates 5 and 7 or also by a small intermediate member 19. The amount of rail deflection *f*₁ is equal in both instances. In the arrangement shown in Fig. 7 the maximum amount which both plates 5 and 7 deflect is also only equal to *f*₁. On the other hand in the arrangement shown in Fig. 6 which diagrammatically represents Fig. 5, the two plates 5 and 7 are deflected toward each other the amount *f*₁ at the rim *a* of presser 17 and at the corresponding rim of supporting rail 2, whereas both plates are more strongly deflected at their centers, the deflection being there equal to *f*₂. Thus it will be clearly seen that under otherwise equal conditions the volume of the chamber is decreased a greater amount by using the arrangement diagrammatically represented in Fig. 6 than in case of the arrangement illustrated in Fig. 7.

What I claim is:

1. In a railway contact device, the combination of a pressure vessel adapted to contain mercury and disposed underneath the rail and suitably supported to remain in contact therewith, said vessel having a heavy top plate flexible only under the weight of a train and adapted to thereby exert a pressure on the mercury without counter-deflection due to the mercury, and a contact vessel containing electric contact terminals adapted to be connected by the mercury, said vessel being disposed adjacent to and connected with said pressure vessel to permit the mercury expelled from the pressure vessel to rise in said contact vessel to make the desired contact.

2. In a railway contact device, the combination of a pressure vessel adapted to contain mercury and disposed underneath the rail and suitably supported to remain in contact therewith, said vessel having a heavy recessed metal top plate flexible only under the weight of a train and adapted to thereby exert a pressure on the mercury without counter-deflection due to the mercury, and a contact vessel containing electric contact terminals adapted to be connected by the mercury, said vessel being disposed adjacent to and connected with said pressure vessel to permit the mercury expelled from the pressure vessel to rise in said contact vessel to make the desired contact.

3. In a railway contact device, the combination of a pressure vessel adapted to contain mercury and disposed underneath the rail and suitably supported to remain in contact therewith, said vessel comprising two heavy recessed plates fitting tightly together at their rims, and flexible only under the weight of a train and adapted to thereby

exert a pressure on the mercury without counter-deflection due to the mercury, and a contact vessel containing electric contact terminals adapted to be connected by the mercury, said vessel being disposed adjacent to and connected with said pressure vessel to permit the mercury expelled from the pressure vessel to rise in said contact vessel to make the desired contact.

- 10 4. In a railway contact device, the combination of a pressure vessel disposed underneath the rail, adapted to contain mercury and having a heavy top plate responsive to deflection by the rail only under the train
15 weight, a contact vessel disposed in close

proximity to said pressure vessel containing electric contact terminals adapted to be connected by the mercury, said vessel having a short communication with said pressure vessel to permit the mercury expelled from the 20 pressure vessel to rise in said contact vessel to make the desired contact.

In testimony whereof I have signed my name to this specification in the presence of two witnesses.

FRIEDRICH PROCHASKA.
